UNITED STATES PATENT OFFICE.

PAUL GERLACH, OF SASKATOON, SASKATCHEWAN, CANADA; AGNES M. GERLACH
EXECUTRIX OF SAID PAUL GERLACH, DECEASED.

ADJUSTABLE STRAW GUIDE FOR BINDERS.

Application filed December 21, 1923. Serial No. 682,035.

To all whom it may concern:

Be it known that I, PAUL GERLACH, a subject of the King of Great Britain, residing at Saskatoon, Province of Saskatchewan, 5 Dominion of Canada, have invented certain new and useful Improvements in an Adjustable Straw Guide for Binders, of which the following is a specification.

This invention relates to an improved 10 means for use in connection with grain binders to accurately assemble the grain into a sheaf without loss thereof.

The primary object of this invention is 15 the provision of an attachment for grain binders and the like which is of relatively simple formation, but which will very efficiently guide flowing grain of varying lengths into such relation that all of the grain may be bundled into sheaves without 20 loss thereof.

It is well known to agriculturists using 25 grain binders that it is difficult to bundle all of the grain or straw into sheaves. Very material losses sometimes result because the grain or straw is not of the particular length 30 for which the binder is adjusted. Because of such, loss is occasioned in a great many instances because the straw is relatively short. Another instance is the fact that the straw varies in length during the cutting 35 thereof. Again, during windy weather it is very difficult to keep the binder reel adjusted in proper position, and the wind boards do not always effectively take care of maintaining the grain or straw in the proper 40 position for binding the same into sheaves. Very often in cutting ripe, stiff, fibered straw of any length the operation of the binder elevators is not suitable for the proper 45 binding of the grain into sheaf assemblage. It is well known that with this type of straw the grain is diagonally disposed upon the elevators, so that as it begins to leave the elevator canvass at the top, the most forward ends of the straw will fall toward 50 the deck and this of course lifts the rear of the straw so that the fast moving elevator will engage the same and shove it out of the proper relation upon the deck, preventing the proper guiding thereof into 55 the sheaf. With the improved adjustable straw guide the disadvantages incident to the ordinary binder, as above enumerated, are overcome and the straw is guided into a proper relation with respect to the packer.

mechanism of the binder so that no loss of grain or straw results.

A further object of this invention is the provision of a grain binder straw guiding attachment of the above mentioned character which is very flexible in operation, and will retain the sheaf in proper relation until the time for discharge thereof from the grain binder deck.

Other objects and advantages of this invention will be apparent during the course of the following detailed description.

In the accompanying drawings, forming a part of this specification, and wherein similar reference characters designate corresponding parts throughout the several views.

Figure 1 is a perspective view of a grain binder of conventional construction, showing the improved straw guide attachment 75 as embodied therein.

Fig. 2 is a side elevation of the improved straw guide attachment as used in connection with deck details of a binder.

Fig. 3 is a view illustrating the details 80 shown in Figure 2, however, showing the improved straw guide mechanism adjusted for guiding flowing straw or grain into proper sheaf bearing relation.

Figs. 4 and 5 are other views illustrating 85 different adjustments of the straw guide mechanism.

In the drawings, wherein for the purpose of illustration is shown but the preferred embodiment of this invention the letter A 90 may generally designate a binder of conventional construction, associated with which is the improved adjustable straw guide mechanism B.

Referring to the binder A, the same may 95 preferably include a frame 10; the ordinary reel 11; horizontal platform structure 11a; inclined elevator mechanism 12; deck construction 13; packer mechanism 14 associated with the ordinary deck slot 15; and 100 bundle carrier 17.

The deck construction 13 is preferably 105 formed of two sections, as in conventional binder construction and connected in any appropriate manner to the frame 10 so that they are inclined at an acute angle to the horizontal at one side of the frame. The hood or cover 20 is carried in any approved manner over the top portion of the deck 13, and at the front thereof.

Referring to the improved adjustable guide means B, the same includes a sheet 30 of galvanized sheet metal or any analogous material, which inherently will assume a plane, but which is flexible in character so that it may be arcuately adjusted or rolled as will be subsequently described. This sheet 30 is preferably attached to the deck 13 of a binder A as by nail or other securing elements 31 and 32 adjacent the front edge 33 in proximity to the slot 15 which is adapted to receive certain details of the packer mechanism of the binder. The lower marginal edge 35 of the sheet 30 is preferably flush with or lies against the lower edge portion 36 of the deck 13. The upper margin 37 of the flexible sheet or guide member 30 lies adjacent the top marginal edge of the deck 13, and along this portion toward the front edge 33 of the sheet 30; said sheet may be disposed beneath the overlapping flange which is in practically all instances provided upon the decks of binders, and which is shown at 40 in Figure 1 of the drawings. This flange 40 is only of sufficient length to extend partly along the sheet 30 and interferes in no manner whatsoever with the adjustable rolling of the same to effect the purpose to be subsequently described. The sheet 30 is longer than the deck portion to which it is secured, and extends for a considerable distance beyond the rear edge 41 of the deck 13, substantially as is illustrated in Figure 2 of the drawings. The lower rear corner of the sheet 30 is removed, providing a beveled edge 45 which is diagonally disposed on the plate 30, and at an obtuse angle with respect to the lower marginal edge 35 and the rear marginal edge 46 of said sheet.

Suitable means 47 may be provided to effect the adjustable positioning of the sheet 30 in a desired manner to guide grain or straw of a particular kind or size; this construction 47 preferably including a flexible cable 48, such as a rope, which at one end is connected to a spiral expansion spring 49; the spiral expansion spring 49 at its opposite end with respect to connection with the cable 48 being connected, as by a hook 50, at the corner on the flexible sheet 30 defined by intersection of the beveled edge 45 with the rear edge 46. The hook 50 is thus positioned upon the guide sheet 30 at a point rearwardly of the lower marginal edge 35, substantially one-third of the distance from the lower to the upper marginal edges of said sheet, and which has been provided for the purpose of rolling the sheet in a proper manner to guide the flowing straw. The cable 48 from its connection with the spring 49 is diagonally extended across the sheet 30 toward the upper front corner thereof and is trained over a swivel pulley 53 which is carried by the hood or cover 20

of the binder. From the pulley 53 the cable 48 extends to the forward portion of the hood 20 where it is trained about a second pulley structure 55 and is then returned toward the rear of the binder in a length 56. An attaching bracket 57 is preferably connected at the rear edge of the hood 20, providing a pair of spaced fingers between which the length 56 of the cable 48 may be placed, so that any of a series of knots 60 may engage said fingers to retain the cable in a desired position. As is illustrated in Figure 1 of the drawings the cable 48 from the attaching bracket 57 may extend for a loose connection with the seat 62 of the binder A. In operation, assuming that it is the desire to use the binder without recourse to the use of the straw guide attachment B, it is merely necessary to set the cable 48 with respect to the bracket 57 as to permit the sheet 30 to flatten itself upon the deck 41, into substantially the position shown in Figure 2. In the use of the improved attachment for the guiding of grain or straw into proper assembled relation whereby to prevent loss of any of the same it is merely necessary for the operator in the seat 62 to grasp the cable 48 and draw the same toward him. This will flex the sheet 30 by starting the rolling of the same in a diagonal manner from the lower rear corner thereof, and the sheet 30 may be placed substantially as is illustrated in Figure 3 of the drawings for the adjustable guiding of straw of relatively long character into the proper relation with respect to the packer mechanism of the binder. The sheet 30 will always tend to diagonally roll toward the upper front corner upon rearward pulling of the adjusting means 47, since it is apparent that the connection of the adjusting means 47 with the sheet 30 is nearer the lower edge of the sheet than the upper edge, and is to the rear thereof. The lower rear corner of the sheet 30 has been removed to prevent the possibility of the discharge arm mechanism of the binder engaging the flexible sheet 30 when it is rolled to a considerable degree for guiding relatively short straw or grain into sheaf bearing relation.

Several adjustments of the sheet 30 have been given in Figures 3, 4 and 5 of the drawings, the latter figure illustrating possibly the greatest adjustment of the sheet 30 to guide flowing straws which are relatively short into proper relation with each other and with the packer mechanism of the binder without loss of any of the straws as is now the case with conventional types of binders.

After the sheaf has been formed on the deck and the sheet 30 has properly guided the straws to form the sheaf, in some instances, as where the sheet 30 is rolled on a small radius some means must be provided

so that the sheaf will roll off the deck sheet 30 at the lower arcuate corner thereof. The weight of the sheaf furnishes sufficient pressure to accomplish this function, and the 5 flexible character of the sheet 30 together with the fact that the same is supported in its guiding rolled relation by the adjusting mechanism 47 at a point above the lower edge 35 furnishes the means which will permit 10 the sheaf to pass off the deck. It is easy to understand that the pressure of the sheaf on the lower portion of the sheet 30, after the sheaf has been formed, will be sufficient to rock the lower rolled portion of 15 the sheet 30 to permit of its displacement. The spring 49, incident to its extensible character also aids in the flexibility of the guide member 30 to perform the functions for which it is adapted.

20 In order that the guide member or sheet 30 may have the requisite flexibility a diagonal strip of spring metal 65 may extend from the lower rear corner of the sheet 30 as provided by the juncture of the beveled 25 edge 45 with the rear edge 46 to the upper forward corner of said sheet. In lieu of this means of providing the required resiliency in the sheet 30 the same may be formed of a pair of sheets in superposed relation, of relatively thin gage.

From the foregoing description of this invention it is apparent that an attachment has been provided which is of an improved character and will properly guide straws of 35 varying lengths into proper sheaf forming relation. The flexibility of the guide member 30 together with the flexibility of its adjusting and supporting means 47 enables the attachment to support the grain or straw in 40 a proper relation until the sheaf is formed, thus obtaining an advantage which is not present to an efficient degree in expedients now used for such purpose. After the sheaf has been released the sheet 30 will, of course, 45 incident to its inherent tendency snap back into the adjusted position in which it has been set.

Various changes in the shape, size, and arrangement of parts may be made to the 50 form of the invention herein shown and described, without departing from the spirit of the invention or the scope of the claims.

I claim:

1. In a straw guiding attachment the combination with a binder including a deck, 55 deck hood, and packer mechanism, of a sheet of flexible material with an inherent tendency to assume a flat relation, means securing said sheet of material to the binder 60 deck adjacent the packer mechanism thereof so that the rear portion thereof is free to be rolled over the deck, a flexible cable, means connecting the cable to the deck hood

of the binder, and means connecting an end 65 of said cable to a lower portion of the sheet whereby upon drawing of the cable taut the sheet may be rolled in a diagonal manner over the deck as a guide for flowing grain.

2. In a sheaf forming attachment the combination with a binder including a deck, 70 deck hood of a sheet of flexible material, means connecting the sheet of flexible material to the binder deck so that the same may be rolled with respect to the binder 75 deck to provide a guide for straw flowing over the deck, a cable, means connecting the cable for adjustment to the hood of the binder deck, and a spring connecting said cable to a portion of the sheet whereby upon 80 drawing of the cable taut the sheet may be rolled to provide a straw guide.

3. In a sheaf forming and supporting attachment the combination with a binder including a deck, deck hood, and packer mechanism, of a substantially polygonal shaped sheet of flexible metal having the lower rear corner thereof removed, means connecting the sheet of material to the deck of the binder adjacent the packer mechanism of 85 the binder so that the rear portion of the sheaf may be flexed over the deck, a cable of flexible character, pulleys forwardly and rearwardly carried by the hood of the binder, means training the cable over said 90 pulleys so that it diagonally extends from the rearward pulley toward the lower rear corner of the sheet of flexible metal, a spring connecting the cable to the rear portion of the flexible sheet of material upwardly of 95 the lower edge of said sheet of material, and means for securing said cable in a desired position so that the sheet of material 100 may be supported in a diagonally rolled relation of a required degree.

4. In a guide attachment for binders the combination with a binder including a deck of a flexible sheet of metal, means for connecting the sheet at one end to the deck of the binder so that the other end is free to 105 be rolled, and means connected with said sheet at the lower rear corner of the free end for rolling the sheet upwardly and diagonally from said corner across said sheet to provide an arcuate guide for grain.

5. In a grain adjusting mechanism for binders the combination with a binder including a deck, and packer mechanism, a flexible sheet of material, means attaching the sheet to the deck of the binder adjacent to the packer mechanism so that the outer portion thereof is free, and means resiliently connected at the free outer portion of said sheet for rolling the sheet towards the packer mechanism.

PAUL GERLACH.
